[57] CLAIM

The ornamental design for a touch-sensitive cursor controller, as shown and described.

DESCRIPTION

FIG. 1 is the perspective view of a touch-sensitive cursor controller showing my new design;
FIG. 2 is the front elevational view thereof;
FIG. 3 is the rear elevational view thereof;
FIG. 4 is the left side elevational view thereof;
FIG. 5 is the right side elevational view thereof;
FIG. 6 is the top plan view thereof; and,
FIG. 7 is the bottom plan view thereof.

The cord is shown broken in the views to indicate an indeterminate length.
